GAS BURNER

Arthur G. McKee, Cleveland, Ohio

Application October 14, 1938, Serial No. 235,015

6 Claims. (Cl. 158—109)

This invention relates to the combustion of gaseous fuel and more particularly to an improved gas burner and valve means for controlling same which is especially adapted for use in connection with heating devices such as blast furnace hot blast stoves, steam generating boilers and the like, particularly when lean fuel gases such as blast furnace gas are burned.

In burning large volumes of gas numerous arrangements of air and gas outlet ports and air and gas mixing devices have been proposed and used. Efficient combustion, especially of lean, low heat value gas, such as blast furnace gas, is usually obtained by premixing the gas with air and then forcing the mixture into the combustion chamber at a relatively high velocity which is greater than the rate of flame propagation to prevent combustion from traveling back to the mixing device and destroying it by high temperature.

In the usual type of hot blast stove an opening is provided in the lower part of the combustion chamber through which a removable gas burner is inserted when it is desired to heat the stove. When the stove is placed on blast the burner is withdrawn and a cover plate must be bolted in place over the opening into the combustion chamber. As air pressures of from 15 to 30 pounds per square inch exist in the stove when on blast, difficulty is sometimes experienced due to leakage or to failure of the bolts which secure the cover plate in position. Cover plates have been blown off from stoves of this type with resulting damage to equipment and danger to the operators. In my improved gas burner construction, as applied to hot blast stoves particularly, the burner always remains in position in the stove and the necessity of installing and removing a pressure retaining cover plate is eliminated. The pressure in the stove when on blast acts to hold the burner valves in closed position and thus the disadvantages and dangers of the removable type of burner are completely eliminated.

It is among the objects of my invention to provide apparatus for burning gas in which the mixture of air and gas takes place substantially at the point of combustion and with which relatively low air and gas velocities may be used. Other objects of my invention are the provision of a gas burner which will occupy a small space for the volume of gas which can efficiently be burned thereby; the provision of a short flame burner for the combustion of lean gases without damage to the burner from the heat of combustion; the provision of a gas burner which will intimately

mix the required quantities of air and gas, regardless of the volumes of air and gas supplied and which may be economically and conveniently constructed substantially entirely of refractory materials so as to withstand the heat of combustion; the provision of a gas burner in which any accumulation of baked on deposits of dust, etc., in the gas passages is discouraged and in which any deposits which do form can readily be removed; the provision of a gas burner with which combustion occurs quickly, very close to the burner gas and air outlets and with a very short flame; the provision of a gas burner and valve control therefor in which an accurate proportioning of the gas and air may be readily and accurately obtained; the provision of a control valve for the gas supply of a hot blast stove or the like in which back pressure, when the stove is on blast, cannot cause entry of heated air into the gas supply pipe with resulting combustion or explosion and gas cannot back into the stove; the provision of a gas burner and control valve arrangement for blast furnace hot blast stoves or the like by which the necessity of withdrawing the air and gas supply pipes and closing the opening in the stove wall therefrom when the stove is put on blast is eliminated and which will supply the necessary large quantities of air and gas required for modern high stove temperature operation; the provision of a hot blast stove burner and valves therefor which are rapidly operable and entirely safe; and the provision of an extremely efficient burner and control valve mechanism for the combustion of gas which is simple in construction and requires a minimum of labor and expense for upkeep and maintenance.

The above and other objects of my invention will appear from the following description of one embodiment thereof, my invention being illustrated in the accompanying drawings as applied to a blast furnace hot blast stove and to a steam boiler furnace, in which—

Figure 1 is a fragmentary side elevation of a hot blast stove which includes my improved gas burner and control therefor.

Figure 2 is a horizontal cross-sectional view taken on line 2—2 of Figure 1.

Figure 3 is a vertical cross-sectional view through the air and gas flues or passages, taken on line 3—3 of Figure 2.

Figure 4 is an enlarged vertical cross-sectional view through the gas and air distributing housing and control valve mechanism.

Figure 5 is a fragmentary cross-sectional view generally similar to Figure 4 but showing only

the structure of the refractory material which defines the air and gas passages and the tubular metallic air and gas diffusing members.

5 Figure 6 is a horizontal cross-sectional view taken on line 6—6 of Figure 5.

Figure 6A is an enlarged fragmentary cross-sectional view illustrating a supporting bolt arrangement for attaching the refractory blocks to the top cover plate of the valve housing structure.

10 Figure 7 is a horizontal cross-sectional view taken on line 7—7 of Figure 5.

Figure 8 is a horizontal cross-sectional view taken on line 8—8 of Figure 5 through a gas port of the burner and also illustrating the wall of the 15 hot blast stove combustion chamber and the supporting and enclosing wall structure for the valve housing and burner passages or flues.

Figure 9 is a view generally similar to Figure 8 but taken on line 9—9 and representing a cross-20 section through an air port.

Figure 10 is a vertical cross-sectional view of a modified form of my invention applied to a steam boiler and having the flues arranged vertically.

25 Figure 11 is a front elevation of a burner assembly shown in Figure 10.

Figure 12 is a vertical cross-sectional view taken substantially on line 12—12 of Figure 11.

In Figures 1 to 9 of the drawings I have shown 30 my invention as applied to a typical blast furnace hot blast stove which is rather diagrammatically illustrated at 1 and which includes the usual combustion chamber or zone 2. Although the illustrated installation is particularly adapted 35 to replace the original removable gas burner in the stove 1 it will be understood that the advantages of my burner will also be secured on original installations.

Referring particularly to Figures 1, 2 and 3, 40 alternately horizontally arranged air and gas passages form a substantially rectangular flue structure, generally indicated at P, which extends through the wall of the stove 1 adjacent the bottom of the combustion chamber 2. Externally of the stove 1 are the air and gas valves 45 and the distributor housing which is generally indicated at A. Air is supplied to this housing through a pipe 3 and the combustible gas through a pipe 4. As will be more fully explained later, 50 separate valves are supplied for controlling the supply of gas and air to the burner. These air and gas valves are mounted upon and operated by valve stems 5 and 6 respectively, which extend up through the top of the housing A and are 55 connected at their upper ends to cables 7 which pass over suitable sheaves 8 and 9 mounted on the frame structure 10. Counter weights 11 assist in the operation of the air and gas valves and chains 12 are provided with adjustable hook 60 members 13 at their lower ends which are adapted to be hooked into the bracket 14 when 65 their valve stems are in raised or open position and be hooked into bracket 15 when the valve stems are in lowered or closed position.

65 Referring to Figure 4, the housing A includes metal walls 16, a metal bottom plate 17 and a metal top plate 18. These are suitably secured together as by riveting or welding and are lined on their inner surfaces with refractory tile 19. 70 Air and gas pipes 20 and 21 extend down and connect to the housing A and are provided with flanged upper ends 22 and 23 which form supports for valve seats 24 and 25 respectively. The air inlet pipe 3 is secured to the top of the valve seat 24 and the vertical cylindrical portion 26

of the gas inlet pipe 4 is similarly bolted through the valve seat 25 and the flange 23 of the pipe 21. It will be seen that a rigid assembly is provided by the housing A, the pipes 20 and 21, the valve seats 24 and 25 and the air and gas inlet conduits 3 and 26.

5 The air supply to the burner is controlled by the air valve 27. As seen in Figure 4 this valve is in its elevated position (with the hook 13 of the chain 12 secured to the lower bracket 14 as shown in Figure 1) and is seated against the valve seat 24 thus shutting off the supply of air which is under suitable pressure in the pipe 3. The valve stem 5 extends out through the wall of the pipe 3 through a suitable bushing or packing 28. When the valve is in its lowest position 15 27', as shown in dot and dash lines in Figure 4, the maximum quantity of air will pass through the pipe 3 and the pipe 20 into the air flues in the housing A. If the valve 27 be elevated from its position 27' enough to reduce the area of the discharge opening from the pipe 20 into the air chamber 43 the amount of air supplied will be reduced until, when the valve is seated against the seat 24, the air supply will be entirely shut off. A separate throttle valve, indicated at 32' (Fig. 4) is preferably inserted in the air inlet pipe and this valve may be employed to vary the flow of air into the chamber 43 and the valve 27 maintained either in full open or completely 25 closed position.

The valve stem 6 carries at its lower end a gas valve 29 and, at an upwardly spaced point, a bleeder valve 30. In Figure 4 the valve is shown in its raised position in which the gas valve 29 is seated against the seat 25, thus closing the passage to the pipe 21 and into the housing A and the gas flues which lead to the combustion chamber. When in this position the bleeder valve 30 is lifted off of its seat 31 on the top of the 35 upwardly extending cylindrical chamber 26. In burner installations of the type described a gas throttle and shut-off valve of any suitable type, indicated in dot and dash lines at 32, is supplied to shut off or throttle the gas ahead of 40 the burner. In operation, after the valve 32 is closed, the valve 29 will be elevated into closed position and the valve 30 will be open providing a free communication to the atmosphere through the opening in the valve seat 31. Thus, if any 45 gas should leak past the valve 32 it will escape to atmosphere and cannot enter the combustion chamber. Furthermore, if, due to the back pressure on the valve 29 when the stove is on blast, heated air should escape past the valve 50 seat 25 it will not enter the gas supply main but will pass freely to atmosphere through the valve seat 31. By the provision of the bleeder valve 30 the danger of formation of an explosive mixture 55 in the stove, valve structure or gas main is prevented. The operation is entirely automatic inasmuch as whenever the valve 29 is closed the valve 30 must be open. When the valve 29 is lowered into open position, shown in dot and 60 dash lines at 29' in Figure 4, the valve 30 will seat on its seat 31 and the atmospheric connection be closed. The gas valve 32 may then be 65 opened and gas be supplied to the burner through the pipe 21. Adjustment of the flow of gas into the chamber 44 may be effected either by the 70 valve 29 or the valve 32, as desired, and as explained above in regard to valves 27 and 32'.

The pipe 21 is mounted on the housing A in the same manner as the air pipe 20 and it serves as a support for the valve seat 25 on which the 75

gas supply pipe 26 is also mounted. A removable clean-out plate 33 closes an opening in the bottom of the housing A and facilitates removal of accumulated solid material from the housing. 5 To assist in proper seating of the valve 29 when in elevated position a valve grinding lever 34 is pivotally supported on a clamp 35 on the valve stem 6 and, when not in use, may be retained in position along the stem 6 by means of a retaining ring 36. As seen in full lines in Figure 4 10 the lever 34 is dropped into horizontal position when it is desired to rotate the stem 6 to seat or grind the valve 29 on the seat 25. A swivel connection 37 between the stem 6 and the cable 15 7 permits this valve grinding movement to take place.

My improved method of burning gaseous fuels contemplates the formation of a plurality of alternate relatively thin layers of gas and air. By 20 this arrangement large volumes of gas and air can be discharged into a combustion chamber at relatively low velocities and with complete and rapid combustion of the gas due to the large gas surface in contact with a correspondingly 25 large surface of air and the intimate mixing and mingling of gas and air which occurs immediately upon the gas and air leaving the ports. Short flame, quiet, even combustion results from this method and the harmful vibration and 30 fluctuation which occurs with long flame combustion is avoided. In order to form the desired plurality of alternate layers of air and gas I provide slot-like gas and air ports which are defined by refractory material and which extend through the wall of the stove 1 into the 35 housing A. The alternate arrangement of these ports is clearly seen in Figure 3 in which the gas ports are indicated at 38 and the air ports at 39. Spacing blocks 40 of refractory material 40 hold the refractory plates 40a in the proper spaced relation to form the gas and air ports and the construction of the refractory structure within the housing A is clearly seen from an inspection of Figures 6, 7, 8 and 9.

45 In Figure 6 is shown a plan view of the refractory structure with the metal cover removed. In order to keep the air and gas separated and to direct the air into the air ports and the gas into the gas ports it is necessary to block off 50 certain parts of the housing. A portion of the top layer of refractory blocks which overlie the air and gas chambers 43 and 44 are preferably supported from the metal cover 18 of the housing A by means of suitable bolts shown at 41 in 55 Figures 5 and 6 and illustrated in detail in Figure 6A.

Figure 7 is an illustrative cross-section showing the bottom layer of refractory material, a hole extending therethrough on the gas chamber side so as to permit cleaning through the removable plate 33.

Figure 8 is an illustrative intermediate cross-section of the valve flue and port structure taken through one of the gas flues 38. Any section taken through any other gas flue 38 would be substantially the same and it will be seen that a wall 42 shuts off the chamber 43 from the flue 38. The gas, however, which enters the gas chamber 44 through the pipe 21 may pass freely 65 through the slot or flue 38 into the combustion chamber 2 of the stove 1. Separating and supporting blocks or bricks 40 are arranged in rows and to further assist in supporting the refractory structure individual, preferably stream-lined blocks 45, of the same thickness as the

spacing blocks 40, furnish the necessary support while offering a minimum of resistance to the flow of gas through the flat thin slot shaped flues 38. A door 46 provides access to the interior of the gas chamber 44.

Figure 9 is a cross-sectional view through one of the air flues and is typical of all of the air passages. To prevent premature mixture of the air and gas a baffle wall 47 closes off the gas chamber 44 from the air chamber 43. Spacing 10 blocks 40 are arranged in rows and serve to support the transversely extending refractory blocks 40a which form the top and bottom walls of the flues. Stream-lined spacers 45 are also utilized to give the desired support while permitting free 15 passage of the air from the diffuser pipe 20 into the chamber 43 and through the ports 39.

By blocking off the air passages 39 from the gas chamber 44 and the gas passages 38 from the air chamber 43 by the walls 42 and 47, the 20 gas and air is directed into the proper passages and premature mixture thereof is prevented. There are, of course, as many walls 42 and 47 as there are gas and air ports, each wall extending only from the bottom to the top of a single passage. In Figures 8 and 9 the path of the gas and air is generally indicated by arrows and the discharge thereof in the combustion chamber 2 through the elongated outlet port openings takes the form of a multi-layer sandwich comprising a 30 plurality of relatively thin and long layers of air and gas alternately arranged. The thickness of the layers of air and gas is preferably so proportioned as to provide the proper amount of air in one layer to fully burn the amount of gas 35 which is discharged through one-half of each adjacent gas port, and this relationship will be maintained as long as the air and gas pressures at the ports are maintained substantially constant.

A large total port area in a small space is provided by my arrangement and therefore relatively low gas and air velocities may be used with resulting quiet steady flame. As combustion will take place close to the outlets of the ports 38 45 and 39 a short and efficient flame may be maintained and as the parts of the port structure which are subjected to high temperatures are all made of refractory material no damage thereto will result. My gas and air control valves 50 provide an accurate and easily operable means for opening, and closing and varying the gas and air supply. The valve structure may be made to withstand any back pressure at which the stove may operate when on blast and the necessity of 55 removing burners and attaching a pressure resisting closure plate to the stove wall is completely eliminated. Danger of explosion due to accidental mixing of hot air and gas is prevented by my safety bleeder valve construction. The 60 blast pressure acts on the under sides of valves 27 and 29 to hold them firmly closed when the stove is on blast and this is an important safety feature of my apparatus.

As gas, and particularly blast furnace gas, 65 always contains a certain amount of non-combustible solid material which will deposit upon the flues and ports of the burner, I preferably cover the bottom surface of the flues 38 with loose sand or the like, as indicated in Figure 8. 70 Any solid material which is deposited may be readily removed by merely removing the sand, and baking of the solids to the flue surface, with resultant decree in cross-sectional area thereof, is prevented.

In Figures 10, 11 and 12 I have illustrated an embodiment of my burner in which the flues are arranged vertically rather than horizontally as described above. These figures also show my burner as installed in a steam boiler furnace. The boiler furnace walls are indicated at 50 and the burner is installed to direct the flame into the combustion chamber 51. Gas is supplied to the burner through a gas main 52 and air 10 through the air supply duct 53 which is divided into two branches 54 and 55. A shut-off valve 56 and gas regulating valves 57 are provided in the gas passages. The gas main discharges into an upwardly extending gas chamber 58, the 15 valves 57 being disposed in the lower part of this chamber.

As is best seen in Figure 10 the vertical gas flues 59 open into the chamber 58 through the bulkhead 60. The gas flues extend to elongated narrow vertical gas outlet ports 61 at the furnace end of the burner. The air from the duct 53 is divided by the ducts 54 and 55 and enters the air chamber 62. This air chamber 62 is divided into sections by a partition plate 63 (see Fig. 12) and curved walls 64 and 65. Thus, the air which enters through the duct 55 is divided by the wall 64 and part enters the upper portions of the air flues 66. Another portion of the air entering through duct 55 is directed 30 downwardly and passes upwardly into the bottom portions of the air flues 66. In like manner air entering through the duct 54 is divided by the wall 65 and part is directed down into the air flues 67 and part up into these flues from the bottom thereon. The air flues are closed off from the gas chamber 58 by the bulkhead 60. The reinforcing and supporting wall 68 extends horizontally across the center of the vertical flue structure and may be provided with vertical holes as 40 indicated at 69 to permit mingling of the gas or air in any one flue 59, 66 or 67. With the construction described the air and gas are not permitted to mix until they are discharged through the vertical ports in the boiler combustion chamber. The previously described advantages of proper proportioning of air and gas, intimate and immediate mixing thereof into a properly combustible mixture and efficient short flame combustion are also obtained with my vertical 45 flue construction. When the flues are arranged vertically as described there will be only a very small area of horizontal gas flue surface on which solids from the gas can collect and thus the necessity of cleaning the flues may be largely 55 eliminated. Of course, where the gas burned is sufficiently clean the horizontal arrangement may be used with entire satisfaction.

In the usual blast furnace hot blast stove burner of the type which is removed and replaced by 60 a cover plate when the stove is on blast, the gas and air are discharged into the combustion chamber through a central circular jet and a surrounding annular jet. The gas may be either inside or outside in such an arrangement 65 and it will be apparent that, in the sizes commonly employed, the contact surface between the air and gas jets at the burner is only equal to the circumference of the central jet or approximately 7 or 8 feet. With my improved refractory burner, for the same size stove, it is 70 possible to have a length of air and gas contact at the burner outlet equal to 30 feet or more. This results in a much quicker mixing and burning of the fuel and combustion takes place very 75 close to the sandwiched air and gas outlet ports.

With the prior structures combustion necessarily takes place at a distance considerably removed from the burner outlet and is accompanied by surging of the flame and popping back with explosive force which sets up vibrations harmful to 5 the entire equipment. These difficulties are completely overcome by my improved burner construction with resulting increase in life of the stove structure and reduction in upkeep cost.

In hot blast stoves the heating is effected by 10 the combustion of blast furnace gas which is a lean or low heat value gas. Ordinarily blast furnace gas runs from 90 to 95 B. t. u. per cubic foot whereas natural gas will run in the neighborhood of 1050 B. t. u. per cubic foot and artificial gas, as commonly produced by municipal gas plants, will run about 535 B. t. u. per cubic foot. Perfect combustion of blast furnace gas with air will not develop a temperature higher than approximately 2200° F. By dividing the 15 combustion of such gas into a plurality of adjacent long and narrow slots or zones the heat is distributed evenly over the burner outlet area and by my improved structure which permits of the use of refractory material walls defining the 20 slots I have made it possible to burn lean, low heat value gases such as blast furnace gases with an efficient, smooth, quiet, short flame without danger of burning out the burner structure. In the old type of removable hot blast 25 stove burner the air and gas outlets are made of metal and it is necessary, in order to prevent burning up of the burner nozzles, to employ the long flame combustion where the maximum temperature was reached at a point considerably 30 removed from the metal nozzle. This long flame resulted in the disadvantages noted above. The old style removable burner could not be made of refractory material because the weight of such a structure would render it inoperative. My improved combination, in which the long and narrow, sandwiched air and gas outlet ports co-act with the refractory walls defining the ports, produces a structure wherein lean, low heat value 35 gases can be consumed most efficiently and with 40 a relatively stable and quiet short flame without danger of burning out the burner structure.

In the accompanying drawings I have illustrated my invention as applied to a blast furnace hot blast stove and to the combustion of gaseous 45 fuels in steam boiler plants but is equally applicable to numerous other installations where an efficient burner for large volume of gas is desired. It will be understood by those skilled in the art that variations and modifications in the 50 structural features of my apparatus and in my method of burning gaseous fuels may be made without departing from the spirit of my invention, and I do not, therefore, wish to be limited to the particular steps and structures described 55 herein, but claim as my invention all embodiments thereof coming within the scope of the appended claims.

I claim:

1. In a burner for directing fuel and air into a 60 combustion chamber, a flue structure having a plurality of adjacent flues which are long and narrow in transverse cross-section, a housing having a gas chamber and an air chamber, alternate ones of said flues opening from said gas 65 chamber and the intermediate flues opening from said air chamber, said flues having outlet ports disposed in said combustion chamber, and means for controlling the flow of air and gas to said chambers, said means including an air valve, a 70

75

gas valve, seats for said valves positioned on the up-stream sides thereof, and means for moving said valves in down-stream direction away from said seats to admit air and gas to said 5 chambers.

2. In a burner for blast furnace hot blast stoves, a flue structure including, a plurality of flues having long and narrow outlet ports, said ports being arranged closely adjacent to each other, walls 10 defining a gas chamber and an air chamber, said flues being arranged to connect alternate ports to said gas chamber and intermediate ports to said air chamber, and means for controlling the flow of air and gas to said chambers, said means 15 including poppet type air and gas valves and seats therefor, said valves and seats being so disposed that back pressure from said combustion chamber when the stove is on blast tends to seat said valves and maintain them in closed position.
- 20 3. In combination with a flue structure having a plurality of alternately arranged air and gas flues, a housing having an air chamber connected to said air flues and a gas chamber connected to said gas flues and to an atmospheric bleeder 25 opening, air and gas control valves in said housing, a bleeder valve adapted to control said atmospheric bleeder opening in said housing, and means for interconnecting said gas valve and bleeder valve whereby said bleeder valve will be 30 open when said gas valve is closed and vice versa.
4. In combination with a flue structure having a plurality of alternately arranged air and gas flues, a housing having an air chamber connected to said air flues and a gas chamber connected 35 to said gas flues and to an atmospheric bleeder

opening, air and gas control valves in said housing, a bleeder valve adapted to control said atmospheric bleeder opening in said housing, and means for interconnecting said gas valve and bleeder valve whereby said bleeder valve will be 5 open when said gas valve is closed and vice versa, a conduit connected to discharge gas into said gas chamber between said gas valve and said bleeder valve, and independent gas control means for controlling the flow of gas through said conduit. 10

5. In a burner of the type described, walls defining a plurality of air and gas flues, means for conducting air to said air flues, means for conducting gas to said gas flues, air and gas control valves in said air and gas conducting means re- 15 spectively, a bleeder valve in said gas conducting means, and means for interconnecting said gas valve and bleeder valve whereby said bleeder valve will be open when said gas valve is closed and vice versa. 20

6. In a burner of the type described, walls defining a plurality of air and gas flues, means for conducting air to said air flues, means for conducting gas to said gas flues, air and gas control valves in said air and gas conducting means re- 25 spectively, a bleeder valve in said gas conducting means, means for interconnecting said gas valve and bleeder valve whereby said bleeder valve will be open when said gas valve is closed and vice versa, a conduit connected to discharge gas into 30 said means for conducting gas to said gas flues between said gas valve and said bleeder valve, and independent gas control means for controlling the flow of gas through said conduit.

ARTHUR G. MCKEE. 35
